2,570,270

CIGARETTE TOBACCO PREPARATION AND
FEEDING

Morehead Patterson, New York, N. Y., assignor to
American Machine & Foundry Company, a cor-
poration of New Jersey
Application April 3, 1946, Serial No. 659,365

3 Claims. (Cl. 131—108)

1

This invention relates to a method for supplying shredded cigarette tobacco to a cigarette machine in such a manner as to supply tobacco having various shred lengths in the proportions found most desirable for the production of high quality cigarettes. More particularly it is an object of the invention to feed from separate sources of supply tobacco having different lengths of shreds and to feed such different length tobacco in definite predetermined proportions which have been found by experience to be characteristic of the best cigarettes.

It has been found by screening the constituents of cigarettes having good mechanical qualities such as uniformity of density (or "feel") and of weight, that such cigarettes are characterized by certain ratios between the weight of long tobacco, that of medium length tobacco and that of short tobacco and dust and manufacturers of cigarettes endeavor to maintain this ratio.

However, it is not always possible with the type of tobacco feeds now used on cigarette making machines to obtain the proportions of these constituents required for satisfactory cigarettes. Due to the breakage of the shreds by the card clothing of the feed drum and refuser drum, the accumulation of "shorts" in the bottom of the tobacco feed and other reasons, there may be considerable variation in the proportions of the various constituents of the shredded tobacco delivered from the tobacco feed to the cigarette making machine.

In the usual methods of cigarette manufacture, tobacco in very long shreds of varying length, as it comes from the shredder, is fed between carded rolls to a picker roll and is again fed to another picker roll from which it is delivered to the cigarette maker. This results in breaking up of the very long tobacco into various lengths of shreds, and by running the card rolls and picker rolls at certain speeds it is possible to produce cigarettes having somewhat the proportions of long, medium and short tobacco desired. This is however a matter of considerable uncertainty, because of the variations in the original lengths of the shreds and variation in shred breakage and also because of loss of "shorts" through the bottom of the tobacco feed, and is also affected greatly by changes in moisture content of the tobacco. I propose to control these proportions more exactly.

The proportions of long, medium and short tobacco may vary widely in accordance with the type of cigarette being made and the types of tobacco used. As one example of what is meant

2

by long, medium and short tobacco, it may be stated that the shredded tobacco may be separated into a portion which will not pass through a 2 millimeter mesh screen and can be regarded as long tobacco, a portion of which will pass through a 2 millimeter mesh screen but not a 1 millimeter mesh screen and may be regarded as medium tobacco, and the remainder will pass through a 1 millimeter mesh screen and can be considered as short tobacco and will consist of "shorts" and dust.

One object of my invention therefore is to maintain more accurately than hitherto possible in cigarette manufacture the ratio between long, medium and short tobacco, once the desirable proportions have been established for a given type of cigarette.

Another object of the invention is to provide a novel method for feeding the required proportions of different shred lengths to the cigarette making machine. I have provided a suitable apparatus for this purpose consisting of a series of separate feeders supplied with tobacco shreds of different lengths, each feeder being arranged to deliver various lengths of shredded tobacco in the desired proportions to a conveyor which feeds the shredded tobacco to the feed chute of the tobacco feed. The tobacco is showered from the feed chute on a cigarette paper or web which advances the layer of tobacco so formed into the rod former of the cigarette making machine wherein the tobacco layer is shaped to form a cylindrical tobacco rod and the edges of the cigarette paper are overlapped and sealed to form the cigarette rod. Thus cigarettes formed from the cigarette rod will contain various lengths of shreds in the desired proportions.

The rate at which the tobacco is delivered by the separate feeders to the conveyor should be varied to obtain the desired proportion of shred lengths. Another object, therefore, is to control the rate at which shredded tobacco is delivered from the various feeders to obtain predetermined proportions of shred lengths in the tobacco delivered to the cigarette making machine.

To prepare the longer shreds an apparatus of the type shown in the Rundell Patent 2,184,567 issued December 26, 1939, may be used. However these shreds and the shorter shreds may be separated by screening or by winnowing.

With these and other objects not specifically mentioned in view the invention consists in certain methods hereinafter described and set forth in the appended claims.

In the accompanying drawing which forms a part of this specification and in which like characters of reference indicate the same or like parts:

The figure is an isometric view of a suitable form of apparatus for carrying out my novel tobacco feeding method.

Referring to the figure, it will be observed that my tobacco feeding apparatus may include the endless apron or conveyor 1 of a suitable tobacco feed. The apron 1 may be suitably supported by a roller 3 and a roller (not shown), the roller 3 being continuously driven by suitable mechanism (not shown) to advance the apron 1 with a layer or mat of shredded tobacco deposited thereon into a chute 5 which forms a part of the tobacco feed. The tobacco advanced into chute 5 drops upon a cigarette paper web or endless belt P running through a feed trough 10 forming a part of a continuous rod cigarette making machine of any suitable construction such as shown in the E. D. Smith Patent 1,090,889 issued March 24, 1914.

A series of tobacco feeders 20, 40, 60 and 80 are arranged to feed shredded tobacco to the apron 1 to form a continuous mat of shredded tobacco on the apron. Each of the feeders 20, 40, 60 and 80 may be a vibratory feed of a type shown in Patent 2,239,858 issued April 29, 1941, to C. F. Randolph. The feeder 20 consists of a vibratory deck 22 provided with an upright wall 24 enclosing three sides of the deck 22. The deck 22 is provided with an extension 26 extending across the width of the apron 1 and having a diagonal edge 28 along one side thereof.

The deck 22 is supported by a rod 39 secured to a member (not shown) clamped on the mid-section of a series of flexible vibrator bars 32 whose ends are secured in a stationary frame 34. In the frame 34 is also supported an electromagnet 35 which may be connected by the wires 37 to a source of A. C. or pulsating electric current. An armature 38 is suitably supported on the mid-section of the bars 32 whereby the armature will be periodically attracted to the electro-magnet 35 and then released to flex the bars 32. In this manner the supply of tobacco S on deck 22 will be vibrated obliquely to form a layer T of tobacco of uniform thickness which will be advanced off the deck 22 and along the extension 26 until it is delivered over the diagonal edge 28 upon the conveyor 1. Since the construction of the mechanism for vibrating the deck 22 is similar to that shown in the Randolph Patent 2,239,858, further description thereof is deemed unnecessary. The deck 22 may be provided with a gate 39 which is adjustable vertically on the walls 24. By adjusting the gate 39 vertically to vary the size of the gap between the lower edge of the gate 39 and deck 22 the thickness of the layer of tobacco T advanced upon extension 26 may be varied, and thus the rate at which tobacco is delivered from feeder 20 to apron 1 may be regulated.

The construction of the feeders, 40, 60 and 80 is similar to feeder 20, and each of these feeders may be filled with a supply of shredded tobacco of different lengths. Feeders 40, 60 and 80 are provided with gates 59, 79 and 99 which may be adjusted vertically to vary the thickness of the tobacco layers advanced from the supplies of tobacco in these feeders upon the conveyor 1. By appropriately regulating the positions of gates 39, 59, 79 and 99, the rates at which tobacco is delivered from the feeders may be controlled to obtain a mat M of shredded tobacco on the apron 1. It will be understood that the rate at which tobacco is fed from the various feeders may be also be con-

trolled by varying the amplitude of the vibration of the decks. For this purpose the amount of electric current supplied by wires 37 to electromagnet 35 may be varied by a rheostat, such as shown in Durnig Patent 2,306,380 issued December 29, 1942, or the amplitude of vibration may be regulated in any other suitable manner.

If the feeder 80 is filled with a supply of shredded tobacco larger than 2 millimeter mesh, the feeder 60 with shredded tobacco smaller than 2 millimeter mesh but larger than 1 millimeter mesh, the feeder 40 with shredded tobacco smaller than 1 millimeter mesh but larger than $\frac{1}{2}$ millimeter mesh, and the feeder 20 with tobacco dust finer than $\frac{1}{2}$ millimeter mesh, the rate at which tobacco is fed from the various feeders may be controlled to obtain the desired proportions of shredded size.

If desired the feeder 20 may be supplied with suitable shredded blending tobacco, such as Latakia tobacco, instead of dust. By regulating the rate at which the blending tobacco is fed the desired blend of tobacco will be obtained.

In preparing the shredded tobacco for the feeders 20, 40, 60 and 80 it may be shredded by a guillotine cutter of conventional construction, and the shreds may be screened to obtain the desired shred size. However the different lengths of shredded tobacco may be shredded in a standard tobacco shredding machine and then winnowed into different shred lengths. Moreover the "shorts" which drop from the bottom of a standard tobacco feed may be utilized.

It is desired that the longer shreds not exceed a predetermined maximum length which may be approximately 2 inches or greater. To prepare shreds which are not longer than the predetermined maximum length and will not pass through a 2 millimeter mesh screen a cross cutting apparatus similar to that disclosed in the Rundell Patent 2,184,567 may be used. In the portion of the constituents of a satisfactory cigarette which will not pass through a 2 millimeter mesh screen, shreds whose maximum length does not exceed two to three inches predominate. With the standard guillotine cutter now used for shredding cigarette tobacco various lengths of shreds including some greatly exceeding two or three inches in length will be produced. With the apparatus shown in Rundell Patent 2,184,567 shreds whose maximum length does not exceed two inches or other predetermined maximum length may be obtained, but it will be understood that shreds having a length not greater than 2 inches are preferable.

It will be noted that the shredded tobacco will be fed from the feeders 20, 40, 60 and 80 without substantially changing the lengths of the shreds, whereas with the carded feed drums and refuser drums used heretofore in tobacco feeds breakage of the tobacco shreds occurs. Moreover since the tobacco is delivered from the conveyor 1 to the chute without picking off a picker roll by a pin roll, as is customary in tobacco feeds, breakage of the tobacco shreds will be avoided. Therefore substantially the same proportions of different shred lengths will be maintained in the cigarette rod formed in the cigarette making machine as are obtained by feeding of the shredded tobacco from the various feeders to the conveyor 1.

While I have described my invention in its preferred form, it will be understood that modifications may be made therein and that no limitations upon the invention are intended other than are imposed by the scope of the appended claims.

What is claimed is:

1. A process for making cigarettes comprising providing separate supplies of shredded tobacco of at least three different lengths, one supply containing relatively long shreds which will not pass through a mesh screen of one size, one supply containing shreds shorter than those in the above-mentioned supply but of a medium length which will not pass through a screen of a different and smaller size, and one supply containing relatively short length shreds which will pass through a screen of a predetermined size smaller than the other two, feeding tobacco from each of said supplies in substantially predetermined proportions of said long shreds, medium length shreds and short shreds corresponding to the proportions present in cigarettes having good mechanical qualities to form composite superimposed streams of uniform width of shredded tobacco from the tobacco so fed from said supplies, and without substantially changing the length of the shreds, delivering the composite superimposed tobacco streams directly through a path unobstructed for the width of the composite streams, to a rod forming web of a cigarette making machine to form a cigarette rod having substantially the same proportions of different shred lengths as is fed from said supplies.

2. A process for making cigarettes comprising providing separate supplies of shredded tobacco of at least three different lengths, one supply containing relatively long shreds which will not pass through a mesh screen of one size, one supply containing shreds shorter than those in the above-mentioned supply but of a medium length which will not pass through a screen of a different and smaller size, and one supply containing relatively short length shreds which will pass through a screen of a predetermined size smaller than the other two, continuously feeding tobacco from each of said supplies, in substantially predetermined proportions of said long shreds, medium length shreds and short shreds corresponding to the proportions present in cigarettes having good mechanical qualities to form composite superimposed streams of uniform width of shredded tobacco from the tobacco so fed from said supplies and without substantially changing the length of the shreds, delivering the composite superimposed tobacco streams directly through a path unobstructed for the width of the composite streams, to a rod forming web of a cigarette making machine to form a cigarette rod having substantially the same proportions of different shred length as is fed from said supplies, and controlling the rate of

feed from said supplies to obtain the proportions of the different shred lengths corresponding to the proportions determined in the cigarette having good mechanical qualities.

- 5 3. A process for making cigarettes comprising providing separate supplies of shredded tobacco of at least three different lengths, one supply containing relatively long shreds which will not pass through a mesh screen of one size, one supply containing shreds shorter than those in the above-mentioned supply but of a medium length which will not pass through a screen of a different and smaller size, and one supply containing relatively short length shreds which will pass through a screen of a predetermined size smaller than the other two, mechanically feeding tobacco from each of said supplies, in substantially predetermined portions of said long shreds, medium length shreds and short shreds corresponding to the proportions present in cigarettes having good mechanical qualities to form composite superimposed streams of uniform width of shredded tobacco from the tobacco so fed from said supplies and without substantially changing the length of the shreds, delivering the composite superimposed tobacco streams directly through a path unobstructed for the width of the composite streams to a rod forming web of a cigarette making machine to form a cigarette rod having substantially the same proportions of different shred lengths as is fed from said supplies.
- 10 15 20 25 30 35
- proportions of different shred lengths as is fed from said supplies, and mechanically controlling the rate of feed from said supplies to obtain the proportions of the different shred lengths corresponding to the proportions determined in the cigarette having good mechanical qualities.
